INVENTOR:
EUGEN HURWITZ
BY Charles R. Mullow
His ATTORNEY.

UNITED STATES PATENT OFFICE

EUGEN HURWITZ, OF BERLIN, GERMANY, ASSIGNOR TO GENERAL ELECTRIC COMPANY,
A CORPORATION OF NEW YORK

BASE FOR INCANDESCENT LAMPS AND SIMILAR DEVICES

Application filed November 15, 1929, Serial No. 407,533, and in Germany December 21, 1928.

My invention relates to bases for electric incandescent lamps and similar devices comprising a glass container, or bulb, having an electric-energy translation device such as a filament sealed therein. My invention relates more particularly to bases for larger lamps or other devices and especially to the so-called skirted base which comprises a lower portion, usually screw-threaded, which engages the socket and an upper portion usually of larger diameter called a skirt which receives the lower portion of the bulb neck. Heretofore these portions have been integral. According to my invention they are separated by an insulating block, through passages in which the leading-in conductors are threaded and effectively insulated from each other. The upper skirt portion of the base and the lower portion thereof are fastened to the said block. One of the passages through the block is lateral so that the leading-in conductor projecting therethrough may be conveniently fastened to the lower shell portion of the base. The other passage may be central so that the leading-in conductor projecting therethrough may be united to the center contact carried by the lower shell portion. One advantage of my invention is that the block takes strains occasioned by knocks and hard usage and thus prevents loosening of the base and breakage of the lamp. Moreover, the matter of uniting the leading-in conductors to their respective terminals is facilitated and their insulation from each other ensured.

In the drawings, Fig. 1 is a vertical sectional view of a base embodying my invention and Fig. 2 is a side elevation of a block forming part thereof.

As shown in the drawings, the base consists of the usual threaded portion 10 and metal skirt 11, both preferably made of metal such as brass. These sections are separated by a block 12 of insulating material such as porcelain and have the passages 13—14 for the leading-in wires. The said block has a collar 17 which serves to insulate and separate the two metal portions 10 and 11. Above and below the collar are a series of peripheral depressions 15 and 16 respective-

ly into which tongues 18 and 19 of the metal portions are punched. Permanent fastening of these parts may be provided by filling the depressions after the tongues are bent therewith into with suitable cement.

What I claim as new and desire to secure by Letters Patent of the United States, is:

1. A base for incandescent lamps and similar articles comprising an insulating block having passages therethrough for leading-in conductors and a collar and upper and lower metal shells united to said block and separated by said collar, said upper shell being shaped so that it may be cemented to a bulb neck and said lower shell being threaded to engage a socket. 60
2. A base for incandescent lamps and similar articles comprising an insulating block having passages therethrough for leading-in conductors and peripheral depressions there- 70 in and upper and lower metal shells united to said block and having tongues engaging said depressions, said upper shell being shaped so that it may be cemented to a bulb neck and said lower shell being threaded to 75 engage a socket.

In witness whereof, I have hereto set my hand.

EUGEN HURWITZ.
